(57) **CLAIM**

The ornamental design for a vent cover, as shown and described.

DESCRIPTION

FIG. 1 is a front and top left perspective view of a vent cover;

FIG. 2 is a bottom plan view of the vent cover shown in FIG. 1;

FIG. 3 is a top plan view of the vent cover shown in FIG. 1;

FIG. 4 is a side elevational view of the vent cover shown in FIG. 1;

FIG. 5 is a back elevational view of the vent cover shown in FIG. 1; and,

FIG. 6 is a front elevational view of the vent cover shown in FIG. 1.

The broken line showing is for illustrative purposes only and forms no part of the claimed design.
